FISHING LURE

Wilmer J. Robinson, 1313 Violet St.,
Bossier City, La. 71010

Filed May 22, 1975, Ser. No. 579,927

Term of patent 14 years

Int. Cl. D22—05

U.S. Cl. D22—27

FIG. 2

FIG. 3

FIG. 4

FIG. 5

FIG. 1 is a top plan view of the fishing lure, showing my new design;

FIG. 2 is a side elevational view thereof;

FIG. 3 is an enlarged cross-sectional view taken along the line 3—3 in FIG. 1;

FIG. 4 is an enlarged cross-sectional view taken along the line 4—4 in FIG. 1; and

FIG. 5 is an enlarged cross-sectional view taken along the line 5—5 in FIG. 1.

I claim:

The ornamental design for a fishing lure, substantially as shown.
